Attorney.

UNITED STATES PATENT OFFICE

WILLIAM F. HELMOND, OF HARTFORD, CONNECTICUT, ASSIGNOR TO UNDERWOOD ELLIOTT FISHER COMPANY, OF NEW YORK, N. Y., A CORPORATION OF DELAWARE

TYPEWRITING MACHINE

Application filed December 23, 1927. Serial No. 242,029.

This invention relates to retarding devices for typewriter-carriages.

An object is to simplify and reduce the expense of construction and to provide a factory-assembled unit attachable to any Underwood machine.

According to the present invention, a compact brake produces a constant retarding action. The brake includes a simple disk mounted upon a shaft carrying a pinion-device which meshes with and raises the carriage-rack from the control of the line-space escapement-mechanism. This disk is pressed by means of a spring against a friction-disk between it and the face of a brake-drum at the outer end of a journal member in which the shaft is mounted. The spring maintains a constant pressure on the disk and is held in place by means of a screw in the end of the shaft for holding it in place thereon. The brake is in such an accessible position in the typewriter-frame that the screw may be easily manipulated with a screw-driver to turn it in or out longitudinally of the shaft, so as to vary the pressure of the spring and regulate the speed. The brake is very small, but it is effective in operation for either small or large carriages, and occupies but very little space.

Other features and advantages will hereinafter appear.

In the accompanying drawings,

Figure 1 is a sectional elevation of an Underwood typewriting and tabulating machine with a carriage speed-regulator according to the present invention applied thereto.

Figure 2 is a perspective view of the carriage speed-regulating mechanism, with parts broken away, showing its relation with respect to the co-operating parts of the machine.

Figure 3 is a plan view with parts broken away to show the speed-regulating mechanism.

Figure 4 is a perspective view of the parts of the speed-regulating mechanism in a disassembled relation.

The typewriting machine is of the regular Underwood construction, of which type-bars 11 are swung upwardly by means of the usual

type-keys 12 and rearwardly to print against a cylindrical platen 13, which rotates on a shaft 14 journaled in a platen-frame 15 mounted in a carriage 16. The carriage 16 is reciprocable along rails 17 supported by the frame 18 of the machine, and a spring-drum 19, mounted within the frame, is connected by means of a strap 20 for driving the carriage from right to left along said rails. The letter-space movements of the carriage are controlled by the usual escapement 21 which is connected with the carriage by means of a pinion 22 engaging a rack 23. The rack 23 is carried by arms 24 at each end of the carriage, whereby it may be swung out of engagement with the pinion 22 to permit the carriage to reciprocate along the rails independently of the escapement-mechanism, whereby, when the rack is released from the pinion, the spring-drum will operate to drive it forwardly for tabulating.

The typewriting machine is provided with tabulating mechanism, parts of an Underwood decimal tabulator being illustrated. The tabulator includes a plurality of keys 25, which are operable to project counter-stops 26 into the path of settable stops 27 mounted on a rack 28 on the carriage 16. Each of the counter-stops 26 has a cut-out portion or shoulder 29 engaging a universal bar 30 mounted on a rock-shaft 31, so that, when a counter-stop is projected, the shaft 31 is rocked and draws down a link 33 through the intermediary of a rock-arm 32 to swing the speed-regulator 34 carrying a pinion 35 fast on the speed-regulator shaft 36 into mesh with the carriage-rack 23. An anti-friction roller 37 loose upon said shaft 36 at the same time engages the rack 23 to lift it out of engagement with the escapement-pinion 22, permitting the carriage to be driven forward by the aforesaid spring-drum 19 and connecting strap 20 until a stop 27 is intercepted by the projected counter-stop 26.

The speed-regulator 34 includes an extending shaft or stud 38 which, as disclosed, has one end 39 in screw-threaded engagement with a socket 40 on the brake-casing 41. This shaft is pivotally mounted in bearing 42 extending from the standard 43 contain-

ing the tabulator counter-stops 26, and is provided with an arm 44 on its other end having pin-and-socket connection with the link 33 whereby, when the link is drawn down, the shaft 38 will be rocked to release the rack 23 from the escapement-pinion 22.

Extending forwardly within the machine-frame the brake-casing 41 is provided with a shaft-casing or mount 45 for the shaft 36.

- 10 Fast upon the shaft 36 is the pinion 35, which is rotated by the rack 23 during tabulating operations, and beyond pinion 35 the anti-friction roller 37, which engages the rack-bar, is journaled and maintained in place by means of a screw 46 axially threaded into the end of shaft 36. A steel washer 47 is provided as a wear-plate positioned between the pinion 35 and the end 48 of the shaft-casing 45.
- 15 20 The opposite end 49 of the shaft 36 has a threaded socket 50 for receiving an assembling and regulating screw 51, and is milled off or flattened at 52. This flattened portion provides a longitudinal guide-way for a distance along shaft 36 for receiving a disk 53 and a spring 54, each provided with an aperture 55 corresponding in shape to the section of shaft 36 and its end 49, whereby these members are caused to rotate with the shaft but may slide longitudinally thereon.

25 30 Spring 54 is provided with a plurality of resilient prongs 56 which engage the disk 53 to force it inwardly, and it has an outwardly-extending prong 57 which engages one of the sides 58 of the head 59 of the regulating-screw 51 to prevent its turning or unscrewing when it has once been adjusted in position in the threaded socket 50 in the end 49 of shaft 36. A collar 60 is positioned between head 59 and spring 54 so that the spring will engage along the flattened portion of the end 49 of shaft 36 and permit of adjustment inwardly along the shaft a distance equal to the length of the collar 60, at which time the head of 35 40 45 the screw will be in engagement with the outer end of shaft 36, thereby limiting the inward adjustment of the screw. A friction-disk or washer 61 having an aperture 62 is positioned on shaft 36 to be compressed between the inner face of disk 53 and the face 63 of the brake-casing 41.

50 55 The construction and arrangement of the various parts of the speed-regulator are best shown in Figure 4 in their disassembled arrangement ready to be put together. When the parts are assembled the disks 53 and 61 are within the brake-casing 41, the flange 64 of which extends to cover the peripheral edges of these disks, and the various parts are in 60 65 positions as clearly indicated in the other figures of the drawings.

The brake-casing 41 faces outwardly when the speed-regulator 34 is in position in the frame 18 of the typewriting machine, and the regulating screw 51 may be easily manipulated

lated with a screw-driver so as to vary the compression of the spring 54 against the disks 53 and 61 and face 63 of the brake-casing 41 to adjust the friction between these parts and thereby regulate the speed at which the typewriter-carriage 16 will be permitted to travel during tabulating operations, when the rack-bar is engaged by the pinion 35 and is controlled by the speed-regulator.

70 75 80 85 It will be noted that the journal or mount 45 includes a face 63 and a face 48 at opposite ends thereof; that the action of the spring 54 in rotating with the shaft 36 operates to press the rotating disk 53 towards the stationary brake-face 63 and draws the rotating pinion against the stationary face 48 of the journal to provide two rotating friction elements that co-operate to retard the rotation of the rack-driven pinion 35; and that the friction-washer or disk 61 is loose on the shaft 36 and will be compressed between the rotating disk 53 and the stationary braking face 63.

90 95 100 105 110 It will be further noted that the retarder is an assembled stock unit that is requisitioned from stock to be assembled as a unit upon a machine at the factory, or by a repairman in a far-away locality; that the parts assembled within and upon the mount 45, with the exception of the spring 54, are all the product of the automatic-screw machine; that the assembled unit includes a long shaft transmission disposed at right angles to the traveling carriage-rack, and swingable upon a long trunnion-bearing on the mount and at right angles to the shaft, to shift the pinion in a comparatively straight line into co-operation with the carriage-feed rack; and that the factory-assembled unit is quickly adjusted to a machine by slipping the rock-shaft 38 through the bracket-bearings 42, and adjusting the arm 44 and the connection 33, all the adjustments being secured with a screw-driver.

115 120 125 130 It will be understood that the disk 53 may be fast to the shaft 36, and the pinion 35 may be splined to the shaft, and the spring 54 and adjustments 51 and 60 arranged at the pinion-end of the shaft 36.

Variations may be resorted to within the scope of the invention, and portions of the improvements may be used without others.

Having thus described my invention, I claim:

1. In a typewriting machine, the combination with a traveling carriage having a rack, of a shaft, a journal for said shaft, a pinion upon said shaft at one end of said journal to mesh with said rack, a drum extending from the other end of said journal, a friction-brake including a disk upon said shaft to rotate therewith within said drum, a friction-disk mounted between the disk on said shaft and face of the drum, a spring upon the outer end of said shaft engaging

the disk thereon to press it against said friction-disk and the face of the drum, said disk and spring on said shaft mounted so as to be rotated by the shaft with respect to the drum but movable longitudinally thereof, said spring consisting of a flexible washer having a plurality of resilient inwardly-extending prongs for engaging the disk on the shaft and an outwardly-extending prong operable as a holding member, and a screw in the end of said shaft having its head engaged by said outwardly-extending prong on said spring, said prong normally engaging the head of the screw to prevent it from turning, but yieldable to permit the screw to be adjusted in and out longitudinally of the shaft for operating upon said spring to increase or diminish its pressure against said disk to adjust the retarding action of said brake, whereby the speed of the carriage controlled by the brake may be regulated.

2. In a typewriting machine, the combination with a traveling carriage having a rack, of a shaft, a journal for said shaft, a pinion upon said shaft at one end of said journal to mesh with said rack, a drum extending from the other end of said journal, a friction-brake including a disk upon said shaft to rotate therewith within said drum, a friction-disk mounted between the disk on said shaft and the face of the drum, a spring upon the outer end of said shaft engaging the disk thereon to press it against said friction-disk and the face of the drum, said disk and spring on said shaft mounted so as to be rotated by the shaft but movable longitudinally thereof, a collar slidingly mounted on the end of said shaft beyond said spring so as to maintain the spring in engagement with the shaft, and a screw in the end of said shaft engaging said spring through said collar, said screw being adjustable in and out longitudinally of the shaft for operating upon said spring for adjusting the retarding action of the brake, whereby the speed of the carriage controlled by the brake may be regulated.

50 WILLIAM F. HELMOND.
